UNITED STATES PATENT OFFICE.

JAMES C. COVERT, OF WEST TROY, NEW YORK.

DESIGN FOR A BUCKLE-FRAME.

SPECIFICATION forming part of Design No. 25,075, dated January 21, 1896.

Application filed December 14, 1895. Serial No. 572,220. Term of patent 14 years.

To all whom it may concern:

Be it known that I, JAMES C. COVERT, a citizen of the United States, residing at West Troy, in the county of Albany and State of New York, have invented and produced a new and original Design for Buckle-Frames; and I do hereby declare the following to be a full, clear, and exact description of the same, reference being had to the accompanying drawing, forming a part thereof.

This invention relates to an original design for buckle-frames; and it consists in the peculiar shape and arrangement of the several parts thereof, as shown in the accompanying drawing, wherein—

A designates the end bar having curved ends, B the side bars, and C the opposite end bar. Between the end bars and on the lower edges of the side bars is the flat cross-plate D, from the central upper face of which springs the pillar or post E.

F designates a cylindrical extension pro-

jecting out longitudinally from the center of the cross-bar C, its upper portion lying on a plane slightly above the plane of the cross-bar. At the outer end of the cylindrical extension is a hook G having its point in line with the cylinder.

The essential feature of the design is the frame having the flat central plate and the cylindrical extension on the cross-bar with the hook at its outer end, as shown.

Having thus described the invention, what is claimed as new, and desired to be secured by Letters Patent, is—

The design for a buckle frame, substantially as shown and described.

In testimony whereof I affix my signature in presence of two witnesses.

JAMES C. COVERT.
